UNITED STATES PATENT OFFICE.

ENU BROWN, OF PEEKSKILL, NEW YORK.

HAIR-PIN.

SPECIFICATION forming part of Letters Patent No. 718,188, dated January 13, 1903.

Application filed April 30, 1900. Serial No. 15,024. (No model.)

To all whom it may concern:

Be it known that I, ENU BROWN, a citizen of the United States, and a resident of Peekskill, in the county of Westchester and State 5 of New York, have invented certain new and useful Improvements in Hair-Pins, of which the following is a specification.

The invention relates, primarily, to hair-pins, though it is well understood that the 10 uses to which hair-pins are put are various and are not limited to hair.

The object of the invention is to render the hair-pin easily securable in the hair and readily detached and drawn out from the 15 hair.

Heretofore hair-pins have been bent in a variety of ways. Perhaps the best known form is that in which the tines of a wire hair-pin have been made undulating or crimped, 20 so that these undulations will tend to prevent the hair-pin dropping out or pushing out. Hair-pins have also been made with a concave bend in the top, so that when hidden under the hair they will be held in by 25 strands of hair overlying and resting in the recess formed by the concave bend. It has also been proposed to form a T-shaped head on a wire hair-pin, the shoulders or the horizontal members of the T receiving the hair 30 and holding the pin in place. This form is not, so far as I am aware, in general use, because of the difficulty and inconvenience of detaching it, it being necessary to disengage the hair from both arms of the T before the 35 pin can be withdrawn. The present invention differs from all these in providing a hair-pin between the tines of which there is a single unbifurcated passage which at the head end of the hair-pin turns to one side, so 40 that while forming a shoulder to catch and retain the hair, and thereby retain the pin in place, it also provides for the ready withdrawing of the hair-pin by merely pressing the hair or the pin laterally, so that the strand 45 of hair embraced by the pin will free itself and be guided along the interval between the two tines without the least trouble.

In the drawings two modifications of the pin are shown, Figure 1 being a preferred 50 form, and Fig. 2 a variation of it.

In both figures wire pins are shown, though, of course, the invention is not limited to hair-pins formed from wire, as they may be stamped, cut, or otherwise formed from sheets of shell, horn, or other materials. 55

In both figures the tines are lettered, respectively, A and B. The space between them is lettered C. The head portion D of Fig. 1 is formed by the bending of both tines A and B in the same direction, so that the space between the tines turns to the left and forms a laterally-extending recess or pocket H, as seen in the figure, and the bend F of the tine A forms a shoulder. When the hair is in the recess H, it not only tends to hold the hair-pin in place by resting upon the shoulder F, but it is also preferably confined and kept within the recess H by reason of the interval or space being narrower between the shoulder F and the tine B than at any other point. 60 The inner surface of the tine may be smooth, uninterrupted, and continuous in the recess H, so that all that is necessary to free the pin from the hair is to press the head of the pin toward the left or, what amounts to the same 65 thing, to press the hair toward the right against the tine B, and thereby permit the hair to pass along the smooth surface of the tine B as the hair-pin is withdrawn.

Fig. 2 differs from Fig. 1 in design rather 70 than in principle. The shoulder F is not as abrupt, and the passage or space between the two tines is not enlarged in the same way as Fig. 1. The spaces C and H form a continuous curved passage-way, the blind end of the 75 passage-way being turned back or down toward the points of the pin. Both are alike, however, in presenting an interior shoulder to engage the hair and a smooth guiding-surface continuous with one of the tines for permitting the withdrawal. 80

Obviously some features of the invention may be used without other features and may be embodied in widely-varying forms, particularly as regards the exterior contour. 85 For this reason 90

I claim the following:

1. The improved hair-pin having a plurality of tines connected at one end, and having a single laterally-extending recess adjacent 95 100

to the junction of the tines, said recess being a continuation of the space between the straight portions of the tines, substantially as set forth.

2. The improved hair-pin having a plurality of tines connected at one end, and formed with a laterally and downwardly extending recess adjacent to the junction of the tines, substantially as set forth.

Signed at Peekskill, in the county of Westchester and State of New York, this 14th day of April, A. D. 1900.

ENU BROWN.
